US00D992949S

(12) **United States Design Patent** (10) Patent No.: **US D992,949 S**
(45) Date of Patent: **** Jul. 25, 2023**

(54) **TOASTER**

(71) Applicants: **Alex Gort-Barten**, Crawley (GB);
Leslie Gort-Barten, Crawley (GB)

(72) Inventors: **Alex Gort-Barten**, Crawley (GB);
Leslie Gort-Barten, Crawley (GB)

(**) Term: **15 Years**

(21) Appl. No.: **35/513,846**

(22) Filed: **Sep. 15, 2021**

(80) **Hague Agreement Data**

Int. Filing Date: **Sep. 15, 2021**

Int. Reg. No.: **DM/217574**

Int. Reg. Date: **Sep. 15, 2021**

Int. Reg. Pub. Date: **Mar. 18, 2022**

(30) **Foreign Application Priority Data**

Mar. 16, 2021 (GB) 6124704
